FLOW INTERMITTENT FOR CASED WELLS

Alexander Boynton, San Antonio, Tex.; Sida S. Martin executrix of said Alexander Boynton, deceased

Application August 23, 1943, Serial No. 499,670

10 Claims. (Cl. 121—124)

1

My invention relates to flow intermittents for cased wells, and deals with the general subject of my Patents No. 2,263,565, issued November 25, 1941, and No. 2,262,750, issued November 18, 1941.

The principal object is to provide automatic means for causing a well to flow at predetermined intervals and during predetermined lengths of time.

A further object is to control the duration of the flowing operation and the interval between such operations by means independent of gas pressure within the well.

Another object is to enable a well to be flowed at predetermined intervals and during predetermined lengths of time, without subjecting the producing formation of the well to any pressure from the air or gas employed to lift the well liquid, this result being accomplished by employing a packer or string of pressure tubing surrounding the flow tubing, the annular space between the two strings of tubing being closed hermetically proximate their extreme ends.

A still further object is to provide a flow intermitter which will cause flow devices to operate more efficiently and without manual control at pressures which may be varied by adjusting the intermitter.

Another object is to provide an intermitter which may be operated by pressure fluid ranging in value from only slightly above the atmosphere to that of the pressure fluid employed by it in flowing wells.

A further object is to conserve natural gas and lengthen the natural flowing life of oil wells by closing the wells in before or when their gas begins to break through the well liquid and by opening the wells again when they have built up enough gas to flow them.

Another object is to record the number of flowing operations during known intervals.

In accomplishing the foregoing objects by means of the preferred construction, I employ a piston assembly within two aligned cylinders, each one of the cylinders being connected with a source of compressed air or gas. The pressure is reduced alternately in one of the cylinders and then in the other cylinder by bleeding off the pressure fluid, thereby causing the piston assembly operative within the cylinders to move alternately in opposite directions and to actuate a plurality of valves which control the intermittent flowing operations to accomplish the stated objects.

In the modified form, a pressure regulator con-

2

trols the constant low pressure in one of the cylinders, while a feeder and a bleeder valve are employed to alternately build up and deplete the pressure in the other cylinder until it becomes alternately more and less than that within the low pressure cylinder. The resulting intermittent difference in pressures obtaining in the cylinders containing opposite ends of the piston assembly causes the piston assembly to travel first in one direction and then in the other; thereby operating a plurality of valves to accomplish the foregoing objects.

A latch retards the movement of the piston assembly in both directions, in order that any movement begun will be completed with certainty.

The piston assembly is adapted to operate four valves in the preferred embodiment and two valves in the modified construction. These valves control the duration of the flowing period and the intervals between such periods.

A mechanical counter is actuated by the piston assembly to record the number of flowing operations; all of which will become more apparent from an examination of the following specification and accompanying drawings, in which—

Fig. 1 is a front elevation of the preferred construction.

Fig. 2 is a plan view of the feeder and bleeder valves and platform in Fig. 1.

Fig. 3 is a plan view of Fig. 1.

Fig. 4 is a cross section about on the line 4—4 of Figs. 1 and 7.

Fig. 5 is an enlarged perspective view partially in section of a portion of the operating lever and driving mechanism therefor incompletely shown in Fig. 1.

Fig. 6 is a cross section on the line 6—6 of Fig. 1.

Fig. 7 is a typical horizontal section through the center of the cylinder, piston and latch of Fig. 1, a portion of the piston being in top view.

Fig. 8 is an isometric view, partially in section, showing a portion of the piston member within the cylinder spacer member.

Fig. 9 is a view similar to Fig. 8 but revolved 90 degrees.

Similar characters of reference are employed to designate similar parts throughout the several views.

Referring particularly to the construction employed in Fig. 1, the casing head 3 is employed to form a hermetic seal between the well casing 1 and the flow tubing 2 proximately above the ground surface 4, the tubing being positioned centrally within the casing and surrounded by the annular space 1a.

A flow line connection or tubing extension nipple 5, which may be of the same diameter as the tubing 2, is shown connected to the tubing by the union 2a, which is employed for convenience in assembling the intermitter and removing it from the well. The nipple 5 may be bent, as shown, and joined to a flow line leading to a production tank, not shown. Manifestly this nipple may be considered as an outward extension of the tubing or as an extension of said flow line joined to the tubing.

The nipple 5 is cut and threadedly joined to the tubing valve 157, which may be of the ordinary lubricated plug valve type. The operating lever 158 has one end pressed over or otherwise secured upon the operating shank 157a, into which shank the conventional lubricant screw 157b has threaded connection. The other end of the operating lever 158 is forked into two prongs 158a and 158b (see Fig. 5). These prongs proximate their outer ends may have, and are shown to have large clearance over the drive pin 160 and the roller 162. This clearance diminishes toward the fork of the prongs until at the fork the prongs have only slight clearance over the roller 162. The length of the opening between the prongs 158a and 158b is such that the roller 162 will remain free therein during the arcuate swing of the lever 158.

The drive pin bracket 159 has an opening 159b adapted to register with the slot 11j of the piston member and also has the openings 159c through which the cap screws 165 are adapted to be engaged in their connection within the bosses 11k of the double ribs 11h, as clearly appears in Fig. 5.

The drive pin 160, Fig. 6, which may have right hand threads on one end and left hand threads on the other end, by means of which it may be locked against rotation, has a close fit through the double flanges 159a of the bracket 159 where it is secured by the nuts 163 and 164. The roller 162 has slight internal clearance over the pin 160 and slight end clearance with the flanges 159a of the bracket 159, as appears in Fig. 6.

The central longitudinal bore 160a of the pin 160 is intersected by the cross bore 160b. The lubricator screw 161 is adapted to close the bore 160a. The bores 160a and 160b may be filled from time to time with a lubricant for the purpose of lubricating the roller 162, as also appears in Fig. 6.

The clearance which the prongs 158a and 158b have over the roller 162 provides that the latch will be sprung and the piston assembly will build up a predetermined momentum in its travel before the load of opening or closing the valve 157 will be encountered, as is apparent.

For convenience in assembling and adjusting the stroke of the lever 158, the sleeve 166 may be secured upon the nipple 5 by the welds 166a (see Fig. 4). The adjusting ring 167, threadedly engaged over the sleeve 166, may be locked by the ring 168, also having threaded engagement over the sleeve 166. It is apparent that screwing the adjusting ring 167 upward will raise the outer and inner tubing clamps 38 and 39 supporting the cylinder and piston assembly, and thereby will lengthen the arcuate swing of the operating lever 158, and that the swing of this lever will be decreased by screwing the ring 167 downward, followed by the clamps 38 and 39.

The cylinder assembly consisting of the cylinder spacer member 6, having the external longitu-

dinal reinforcing ribs 6m and the right and left end cylinders 7 and 8, is secured upon the nipple 5 by the upper clamp bolts 40 (Figs. 3 and 4) and the lower clamp bolts 41 (Figs. 3, 4 and 7), which bolts are received through openings in the tubing clamps 38 and 39.

The lower nuts 43 may be beveled and received within corresponding countersinks in the clamps, in order to securely and adjustably position the bolts centrally within the openings through the clamps. The similar upper nuts 42 of the bolts 40 may be similarly engaged through the clamps.

The two lower clamp bolts 41 are engaged threadedly within the bosses 6d and 6e of the cylinder spaced member 6, Fig. 7, while the two bolts 40 are received through openings in the supporting flange 6c, Fig. 4, to which flange these bolts are locked by the upper nuts 42.

The cylinders 7 and 8 are aligned with the spacer member 6. The right end cylinder 7 has its flange 7a secured to the flange 6a of the spacer member by the bolts 9, and the left end cylinder 8 has its flange 8a secured to the flange 6b of the spacer member 6 by the bolts 10.

The piston member 11 (see Fig. 7), has at one end the piston head 11b, closely slidable within the right end cylinder 7, and has at its other end the similar piston head 11c, closely slidable within the left end cylinder 8. The right end piston head 11b has a threaded extension 11d, and the piston head 11c has a similar extension 11e. The U cups or other form of packing 12 and 13 and the spacer rings 14 and 15 separating these cups, each has a central opening which closely receives the threaded extensions 11d and 11e, respectively. The piston member 11 has one of its ribs expanded into the double ribs 11h, having between them the slot 11j (see Figs. 5, 7 and 9). This slot has slight clearance with the sides of the prongs 158a and 158b, and is of such length and depth that the lever 158 is free to swing far enough on either side of a perpendicular line through the center of the valve 157 to open this valve when the piston assembly is at its extreme left, as in Fig. 1, and to close it when the piston assembly moves to the extreme right, the latter movement of the lever being indicated by its position 158'.

The dashpot plunger 16 has threaded connection with the extension 11d, and serves to lock the U cups 12 and the spacer ring 14 together and to hold them assembled against the end of the piston head 11b. Likewise, the U cups 13 and the spacer ring 15 are held assembled against the end of the piston head 11c by the dashpot plunger 17. The U cups 12, closely slidable within the cylinder 7, face the outer end of that cylinder, and the U cups 13, closely slidable within the cylinder 8, face in the opposite direction.

The cylinder 7 has the dashpot pocket 7b. The cylinder 8 has a similar dashpot pocket 8b.

The dashpot plunger 16 is tapered slightly, as appears in Fig. 7, and has very slight minimum clearance, such as one sixty-fourth inch, within the dashpot pocket 7b whenever it engages therein at the end of the piston travel in that direction. Likewise, the dashpot plunger 17 is tapered slightly also, and has similar clearance within the dashpot pocket 8b whenever it engages therein at the end of the piston travel in the opposite direction.

The latch, shown sectionized in Fig. 7, is for the purpose of delaying the movements of the piston assembly until sufficient energy is exerted upon either end thereof to complete the piston

travel in the opposite direction. This latch is similar in operation to that disclosed in my Patent No. 2,329,182, issued September 14, 1943.

The latch shell 18 is secured against the cylinder spacer member 6 by the clamps 29 and 30, engaged with the bosses 6f and 6g, respectively, of the spacer member 6 by the cap screws 31 and 32, respectively. The ends of the shell 18 are closed hermetically by the caps 19 and 20 engaging upon the packings 25a (see Fig. 7).

Proximate its ends, the latch shaft 21 has the latching recesses 21a adapted to be engaged by the latch balls 22. The ball riders 23 urge the latch balls inwardly against the latch shaft and against the ball floors 24 by force of the coiled springs 27, both ball riders and springs having some clearance within the shell 18. Each of the ball floors 24 may be placed in proper position by being engaged threadedly with the shell and secured in proper position by the lock rings 24a. Each gland 26 may have threaded connection within one of the spring bases 28, in order to compress properly the packings 25. The latch balls may be engaged to the maximum depth of the recesses 21a at either end of the shaft 21, as shown, or the force of this engagement may be made less, as required, by screwing the ball floor 24 and the lock ring 24a farther outward, in order that the latch balls will engage less deeply within the recesses 21a. It will be understood that the parts 22, 23, 24, 24a, 25, 25a, 26, 27, and 28 are duplicated at each end of the latch assembly, and that the latch shaft 21, formed the same at both ends, engages with the latch balls in the same manner at each end, although the force of this engagement may be varied at either end by adjusting the position of the ball floor 24 and the lock ring 24a, as above stated.

The latch is operated by the movements of the piston member 11, the latch driver pin 33 being secured at one end within the enlargement 11g of the piston member, as appears in Fig. 7 and having its outer extension 33a of reduced diameter engaged within the central transverse opening through the latch shaft 21. The slot 18a of the shell 18 and the slot 6k of the cylinder spacer member 6 register and are of such width and length that the pin 33 may slide freely therein during the piston movements.

Each end of the latch lubricator pipe 34, Fig. 1, is secured upon the shell 18 by one of the welds 34a. By removing the lubricator plug 35, the latch may be provided with a lubricant which will be confined by the packings 25 and 25a, the latch shaft 21 remaining slidably engaged with the packing 25 during all movements of the latch.

Obviously the latch may be omitted and the difference between the force required to overcome frictional resistance of the parts at rest and in motion may be relied upon to replace the latch.

The mechanical counter 36, many types of which are available, may be secured upon the boss 6h of the cylinder spacer member 6 by the counter cap screws 37 (see Figs. 1, 4, 8 and 9), where it will be actuated to count the well flowing operation by impact of the extension 33a of the latch driver pin 33, slidably within the slot 18b of the latch shell 18.

Proximately beneath the cylinder spacer member 6, the platform 44 is secured upon the nipple 5 by means of the U-bolts 46 engaging around the nipple 5 and through the clamp portion 45. This platform has slots properly positioned to adjustably receive the several strap bolts 54, hav-

ing their nuts engaged against the nether side of the platform for the purpose of securing the several valves shown mounted upon it.

The four valves securely mounted upon the platform 44 may be of the ordinary lubricated plug valve type, as shown. Two of these valves are opened simultaneously by substantially 90 degrees rotation of their operating levers, while the other two are closed simultaneously by a movement evenly divided on either side of a line projected vertically through the center of the valves. The valves are staggered as shown in Fig. 2, two of them facing in one direction and the other two facing in the opposite direction. This arrangement provides that two of the valves will be opening while the other two will be closing, if installed as usually manufactured, without the necessity of reversing their ports.

The four valves 48, 49, 50, and 51 are supported by removable bases which provide that all valves will have their operating shanks on the same horizontal plane, if valves of different sizes be employed. The first feeder valve 48 and its base 58 are secured upon the platform 44 by one of the strap bolts 54. The first bleeder valve 49 and its base 59 are secured upon the platform by a second strap bolt 54. The second bleeder valve 50 and its base 60 are secured upon the platform by the third strap bolt 54. The second feeder valve 51 and its base 60' are secured upon the platform by the fourth strap bolt 54.

The operating lever 62, pressed over the operating shank 48a of the valve 48, has the slot 62a which slidably receives the drive pin 68. The operating lever 63, pressed over the operating shank 49a of the valve 49, has the slot 63a which slidably receives the drive pin 69. The operating lever 64, pressed over the operating shank 50a of the valve 50, has the slot 64a which slidably receives the drive pin 70. The operating lever 65, pressed over the operating shank 51a of the valve 51, has the slot 65a which slidably receives the drive pin 71.

The slots 62a, 63a, 64a, and 65a are of proper length to allow full swing of the levers to open and close the valves.

The slots 44a of the platform 44, which receive the strap bolts 54, are of such length that the position of the valves secured upon the platform may be adjusted so that the operating levers will impart the proper movement to open and close the valves.

The drive pins 68, 69, 70, and 71, which may be of equal diameters and lengths, are each secured within the enlargement 11j of one of the ribs 11a of the piston member 11, and are at such distance apart that the levers 63 and 65 will be parallel with each other and that the levers 62 and 64 will be likewise parallel with each other. The slot 6j of the spacer member 6 (see Figs. 4 and 8) is of such width and length that the drive pins 68 to 71, both inclusive, are slidably freely therein during the full length of the piston stroke in both directions.

The reasons why two valves on one side of the platform will be set to open while the other two valves on the other side close, will appear further on from the functions of these valves and of the conduits into which they are connected.

The pressure supply line 73 has connected into it the valve 73a and the T's 104, 73b, 74, and 75, and terminates at the check valve 77 with which it has connection.

The pressure supply line 73 can be closed by the valve 73a and have communication with the

annular space $1a$ as a source of pressure fluid. This line is shown branched and connected to the boss $3a$ of the casing head for that purpose, the other casing head bosses being closed by the plug $3b$.

The emergency pressure relief conduit 78 has one end connected into the check valve 77 and the other connected into the T 81 .

The first pressure conduit 80 , having connected into it the T 's 81 , 82 , 83 , and 84 , has one end connected with the first receiver 79 and the other end connected with the right side lubricator reservoir 100 .

The first feeder conduit 85 , connected into the T 75 , has connection with both ends of the valve 48 and with the T 83 . The first charger timing valve 86 , which may be a needle valve, is connected into this line between the T 83 and the valve 48 .

The second feeder conduit 90 , connected into the T 74 , has connection with both ends of the valve 51 and with the T 97 . The second charger timing valve 91 , which may be a needle valve, is connected into this conduit between the T 97 and the valve 51 .

The second pressure conduit 94 , having the T 's 96 , 97 , and 98 connected into it, has one end connected into the second receiver 95 and the other end connected into the left side lubricator reservoir 101 .

The first bleeder conduit 87 , having the first bleeder timing valve 88 , which may be a needle valve, connected into it, has connection with the T 82 and both ends of the first bleeder valve 49 , which is adapted to discharge to atmosphere, as appears in Fig. 3.

The second bleeder conduit 92 , having the second bleeder timing valve 93 , which may be a needle valve, connected into it, has connection with the T 96 and both ends of the second bleeder timing valve 50 , which is adapted to discharge to atmosphere, as appears in Fig. 3.

The initial equalizing conduit 105 , having connected into it the T 109 and the valves 107 and 108 , has connection at one end with the second receiver 95 and at the other end has connection with the first receiver 79 .

The valves 107 and 108 will be considered as closed until otherwise specified.

The branch line 105 has connection with the T 104 of the pressure supply line 73 and also has connection with the T 109 .

The oil reservoir 100 , having within it the perforated baffle tube $100a$ secured to it by the weld $100b$, and the similar reservoir 101 , having within it the perforated baffle tube $101a$ secured to it by the weld $101b$, may be filled with oil which will follow the piston assembly and lubricate the cylinders. The lubricator reservoir 100 is connected into the boss $7c$ of the cylinder 7 , and the reservoir 101 is connected into the boss $8c$ of the cylinder 8 . These oil reservoirs may be filled by removing the pressure gauges 102 and 103 or the bushings into which they are shown connected. The plug $7e$ engaged within the boss $7d$ of the cylinder 7 , and the plug $8e$ engaged within the other similar boss $8d$ of the cylinder 8 , provide means for draining the cylinders.

The first charger timing valve 86 controls the time required to build up pressure within the receiver 79 , and the second charger timing valve 91 controls the time required to build up pressure within the receiver 95 . These valves regulate the interval between flowing operations, as will appear further on.

The first bleeder timing valve 88 controls the time required to bleed off pressure from the receiver 79 , and the second bleeder timing valve 93 controls the time required to bleed off pressure from the receiver 95 . These valves regulate the duration of the flowing operations, as also will appear further on.

Operation, Fig. 1

In operation of the intermitter illustrated in Fig. 1 compressed air or gas of proper value to flow the well will be supplied through the pressure supply line 73 via the valve $73a$ or by the well itself. In the beginning, it will be assumed that the piston assembly is at the extreme left as shown in Fig. 7. The valve operating levers then are in the position shown in Figs. 1 and 2. The first bleeder valve 49 and the second feeder valve 51 are open, while the first feeder valve 48 and the second bleeder valve 50 are closed. The tubing valve 157 is open. This begins the flowing operation. The open first bleeder valve 49 is then draining pressure fluid to atmosphere out of the first receiver 79 through the first bleeder timing valve 88 , which valve is so adjusted as to reduce the pressure slowly in the receiver 79 . At the same time, the open second feeder valve 51 is discharging pressure fluid into the second receiver 95 through the second charger timing valve 91 , which valve is adjusted to build up pressure slowly within the receiver 95 . The valve 43 is closed so that it will not allow pressure fluid to enter the receiver 79 while the valve 49 is discharging pressure fluid out of it. At the same time, the second bleeder valve 50 is closed, so that it will not discharge pressure fluid out of the receiver 95 while the valve 51 is discharging into it.

The piston assembly being at the extreme left, as in Fig. 7, and pressure fluid force being built up within the second receiver 95 while similar force is being depleted within the first receiver 79 , it is apparent that the piston assembly will travel to the extreme right and close the tubing valve 157 whenever the difference in pressures within these receivers is sufficient to cause the latch to be sprung.

When the piston assembly moves to the extreme right, opposite from its position shown in Fig. 7, the valves 49 and 51 will be closed and the valves 48 and 50 will be open. This terminates the flowing operation. The first bleeder valve 49 is closed then, in order to allow pressure to build up within the receiver 79 through the open first feeder valve 48 . At the same time the second feeder valve 51 is closed, in order to allow the open second bleeder valve 50 to reduce the pressure within the receiver 95 .

The piston assembly being at the extreme right, it is obvious that with pressure building up within the receiver 79 and being depleted within the receiver 95 , the piston assembly will return to the left and again open the valve 157 whenever the difference in pressures is such as will cause the latch to be sprung.

The tubing valve 157 , being adapted to be opened by approximately a 90 degrees clockwise movement and to be closed by a reciprocating movement, will function to initiate flow through the tubing 2 whenever this valve is open and there is adequate pressure fluid within the annular space $1a$. The piston assembly being moved in the reverse direction from that which opens the valve 157 , this valve, of course, will close

and interrupt the flowing operation; thereby accomplishing intermittent flow of the well.

The latch, for example, may be adjusted to spring at ten or twenty pounds difference in the pressures obtaining within the receivers 79 and 95, provided these receivers are of such capacity that the piston displacement will cause somewhat less than ten or twenty pounds difference in these pressures, as the case may be.

The adjustment of the first bleeder timing valve 88, which bleeds pressure fluid out of the receiver 79, and the adjustment of the second charger timing valve 91, which governs the flow of pressure fluid into the receiver 95, determine the duration of the flowing operations.

The adjustment of the first charger timing valve 86, which controls the inflow of pressure fluid to the receiver 79, and the adjustment of the second bleeder timing valve 93, which controls the discharge of pressure fluid to atmosphere out of the receiver 95, determine the intervals between flowing operations.

For purposes of subsequent discussion, it is assumed that twenty pounds difference in the pressures within the receivers 79 and 95 will be sufficient to spring the latch at either end and to cause the piston assembly to complete its travel in either direction. Then if it be desired, for example, to flow the well for one hour each time, this may be accomplished by slightly opening the first bleeder timing valve 88 so that it will deplete twenty pounds of pressure out of the receiver 79 during one hour, and by slightly opening the second charger timing valve 91 so that it will permit the pressure within the receiver 95 to build up twenty pounds during one hour. Proper adjustment of the valves 88 and 91, of course, will provide any other desired flowing time.

If it be desired that the intervals between flowing operations be two hours, for example, this may be accomplished by adjusting the first charger timing valve 86 so as to allow twenty pounds of pressure to build up within the first receiver 79 during two hours, while the second bleeder timing valve 93 is adjusted to allow twenty pounds of pressure to be depleted out of the second receiver 95 during two hours. Any other desired interval between flowing operations may be obtained by making proper adjustments of the valves 86 and 93, as is apparent.

In beginning the operation of this intermitter, the valves 107 and 108 may be left closed, if it be desired to use low pressures to actuate the piston assembly. In such case, the operating pressures will vary alternately from zero to twenty pounds in opposite ends of the cylinders, because when the device is first installed with the piston assembly positioned as in Fig. 7, there is no pressure in either end of the cylinders, and the valve 51 placing pressure in the left end cylinder 8 is open, while the valve 49, adapted to bleed pressure from the right end cylinder 7, is open also. This practice is to be preferred, if the well will not "pump off" during the flowing operations.

If the well will pump off during the flowing operations, or is apt to do so, preferably the same pressure employed within the annular space 1a to flow the well should be employed also within the cylinders to operate the piston assembly. This is so, because the intermitter is made to terminate automatically the flowing operation by closing the valve 157 whenever gas blows through from bottom when the well cleans itself, if the same pressure is employed to operate the cylinders as that

employed to flow the well. This termination is accomplished by means of the check valve 77.

In employing the same pressure to operate the piston as that employed to flow the well, begin using the intermitter by first opening the valves 107 and 108 simultaneously. Pressure fluid then will enter through the initial equalizing conduit 106 leading out of the supply line 13 and equalize within the receivers 79 and 95. The bleeder valve 49, being then open and depleting pressure within the receiver 79, while the feeder valve 51 discharging pressure fluid into the receiver 95 is open also, it is evident that the same pressure as that employed to flow the well will be employed 15 then to operate the piston assembly, as will be understood from the previous description of this mechanism.

Whenever the weight of the well liquid within the eduction tubing 2 becomes less than the force of the pressure fluid employed to flow the well, the contents of the tubing will be expelled in the form of a slug. As the upper end of this slug passes out through the flow line connection nipple or tubing extension 5, the portion of the slug 20 still remaining in the tubing 2 will move faster and faster as more of the slug is expelled, with the result that pressure fluid will be withdrawn rapidly from the annular space 1a. This causes the pressure within the annular space 1a to drop 25 sharply then, resulting in the opening of the check valve 77, which then discharges pressure fluid out of the receiver 79 into the line 13 and the annular space 1a. When pressure within the receiver 79 drops slightly from the loss of pressure fluid through the check valve 77, the piston assembly 30 will move to the right, thereby closing the valve 157 and terminating the flowing operation, as hereinbefore explained.

Attention is directed to the fact that when the well cleans itself as stated in the preceding paragraph, the first bleeder valve 49 has been reducing the pressure within the receiver 79 since the flowing operation began and that consequently the check valve 77 will be required to reduce this pressure only slightly more in order to terminate the flowing operation. In practice, this is accomplished before the slug is expelled completely or almost instantly afterward, because the operator will adjust the flowing time so that a blow 45 through from the bottom ordinarily will not occur, but if it does occur, this will happen usually when only one or two pounds less pressure within the receiver 79 will result in terminating the flowing operation.

The well being flowed by external pressure, if the valve 73a be opened just far enough to admit into the annular space 1a only enough gas to flow the well, then when the well blows through from bottom, the pressure in the annular space 55 will decrease rapidly.

The fact that the check valve 77 automatically will reduce pressure within the receiver 79 whenever a well cleans itself, and thereby terminate the flowing operation, is one of the important features of this invention; for without such emergency provision, gas from the supply line 13, if the well be flowed by pressure from a source other than the well itself, would waste through the well until the bleeder valve 49 completed the necessary reduction of pressure within the receiver 79 to terminate the flowing operation 65 in the usual manner.

If any pressure intermediate of the assumed minimum pressure of twenty pounds and that 75 employed to flow the well be desired to operate

the piston assembly, that purpose can be accomplished by connecting a pressure regulator into the branch line 105 between the pressure supply line 73 and the equalizing conduit 106.

It is evident that a packer may be set between the tubing 2 and the casing 1, proximately above the lower end of the tubing, in combination with a check valve in the tubing, for the purpose of preventing pressure fluid within the annular space 1a from contacting the producing formations of the well. 5 10

Manifestly the latching mechanism may be disposed in alignment with the piston, as in my co-pending application, Serial No. 412,871, filed September 29, 1941, Patent No. 2,402,728, issued June 25, 1946, such construction being preferred where the added length is unobjectionable. 15

Obviously many minor changes in construction and arrangement of parts, as well as the substitution of mechanical equivalents for parts shown, may be made within the scope and purpose of the stated objects and appended claims, and I reserve the right to make such changes, arrangements, and substitutions.

I claim:

1. In a flow intermitter of the class described, the improvement which includes: right and left end aligned cylinders having dashpot pockets; an operating piston member having one of its ends slideable in one of said cylinders and having its other end slideable in the other of said cylinders, said piston member having dashpot plungers at its ends to enter said dashpot pockets; latching means for delaying the movements of said piston member in each direction; a lubricator reservoir upon the outer end of each cylinder and communicating with the same; a platform held in spaced relation to said piston; a support for said platform and said cylinder, a first feeder valve, a first bleeder valve, a second feeder valve, and a second bleeder valve upon said platform; means for operating said feeder and bleeder valves by said piston, one feeder valve and one bleeder valve being open while the other feeder valve and the other bleeder valve are closed; first and second receivers for pressure fluid; an initial equalizing conduit connecting said receivers; a source of pressure fluid; two valves in said initial equalizing conduit, said initial equalizing conduit having connection between said valves with said source of pressure fluid; a first conduit connecting said first receiver and one of said lubricator reservoirs; a second conduit connecting said second receiver and the other said lubricator reservoir; a first feeder conduit connected into said source of pressure fluid, with both ends of said first feeder valve, and with said first conduit, there being a first charger timing valve in said first feeder conduit; a first bleeder conduit connected with said first conduit and with said first bleeder valve, there being a first bleeder timing valve in said first bleeder conduit; a check valve controlled emergency pressure relief conduit connected between said source of pressure fluid and said first conduit, the check valve opening away from said first conduit; a second feeder conduit connected between said source of pressure fluid and said second conduit and having said second feeder valve therein, said second feeder conduit having a second charger timing valve therein; a second bleeder conduit connected between said second conduit and said second bleeder valve, there being a second bleeder timing valve in said second bleeder conduit; a lubricant in each said lubricator reservoir; and a mechanical counter operated

by force of said piston, whereby gradually augmented pressure fluid force is exerted alternately upon one end of said piston and then upon the other while pressure fluid force is dissipated from the opposite end and the number of each operation is recorded.

2. In a flow intermitter of the class described: right and left end aligned and spaced cylinders; a piston member having one of its ends slidable in one of said cylinders and having its other end slidable in the other of said cylinders; a lubricator reservoir upon the outer end of each of said cylinders; a platform located in spaced relation to said piston; a first feeder valve, a first bleeder valve, a second feeder valve, and a second bleeder valve upon said platform; means for operating said feeder and bleeder valves by said piston, one feeder valve and one bleeder valve being open while the other feeder valve and the other bleeder valve are closed; first and second receivers for pressure fluid; an initial equalizing conduit connecting said receivers; a source of pressure fluid; two valves in said conduit, said conduit having connection between said valves with said source of pressure fluid; a first conduit connecting said first receiver and one of said lubricator reservoirs; a second conduit connecting said second receiver and the other said lubricator reservoir; a first feeder conduit connected into said source of pressure fluid, with both ends of said first feeder valve, and with said first conduit, there being a first charger timing valve in said first feeder conduit; a first bleeder conduit connected with said first conduit and with said first bleeder valve, there being a first bleeder timing valve in said first bleeder conduit; a check valve controlled emergency pressure relief conduit connected between said source of pressure fluid and said first conduit, the check valve opening away from said first conduit; a second feeder conduit connected between said source of pressure fluid and said second conduit an dhaving said second feeder valve therein, said second feeder conduit having a second charger timing valve therein; a second bleeder conduit connected between said second conduit and said second bleeder valve, there being a second bleeder timing valve in said second bleeder conduit; a lubricant in each said lubricator reservoir; and a mechanical counter operated by force of said piston, whereby gradually augmented pressure fluid force is exerted alternately upon one end of said piston and then upon the other while pressure fluid force is dissipated from the opposite end and the operations are numbered.

3. In a flow intermitter of the class described: right and left end aligned and spaced cylinders; a piston member having one of its ends slidable in one of said cylinders and having its other end slidable in the other of said cylinders; a lubricator reservoir upon the outer end of each of said cylinders; a platform located in spaced relation to said piston; a first feeder valve, a first bleeder valve, a second feeder valve, and a second bleeder valve upon said platform; means for operating said feeder and bleeder valves by said piston, one feeder valve and one bleeder valve being open while the other feeder valve and the other bleeder valve are closed; first and second receivers for pressure fluid; an initial equalizing conduit connecting said receivers; a source of pressure fluid; two valves in said conduit, said conduit having connection between said valves with said source of pressure fluid; a first conduit connecting said first receiver and one of said lubricator reservoirs;

a second conduit connecting said second receiver and the other said lubricator reservoir; a first feeder conduit connected into said source of pressure fluid, with both ends of said first feeder valve, and with said first conduit, there being a first charger timing valve in said first feeder conduit; a first bleeder conduit connected with said first conduit and with said first bleeder valve, there being a first bleeder timing valve in said first bleeder conduit; a check valve controlled emergency pressure relief conduit connected between said source of pressure fluid and said first conduit, the check valve opening away from said first conduit; a second feeder conduit connected between said source of pressure fluid and said second conduit and having said second feeder valve therein, said second feeder conduit having a second charger timing valve therein; a second bleeder conduit connected between said second conduit and said second bleeder valve, there being a second bleeder timing valve in said second bleeder conduit; and a mechanical counter operated by force of said piston, whereby gradually augmented pressure fluid force is exerted alternately upon one end of said piston and then upon the other while pressure fluid force is dissipated from the opposite end and a record of the number of operations is shown.

4. In a flow intermitter of the class described: right and left end aligned cylinders; a piston member having one of its ends slidable in one of said cylinders and having its other end slidable in the other of said cylinders; a lubricator reservoir upon the end of each of said cylinders; a first feeder valve, a first bleeder valve, a second feeder valve, and a second bleeder valve, each secured in spaced relation to said piston; means for operating said feeder and bleeder valves by said piston, one feeder valve and one bleeder valve being open while the other feeder valve and the other bleeder valve are closed; first and second receivers for pressure fluid; an initial equalizing conduit connecting said receivers; a source of pressure fluid; two valves in said conduit, said conduit having connection between said valves with said source of pressure fluid; a first conduit connecting said first receiver and one of said lubricator reservoirs; a second conduit connecting said second receiver and the other said lubricator reservoir; a first feeder conduit connected into said source of pressure fluid, with both ends of said first feeder valve, and with said first conduit, there being a first charger timing valve in said first feeder conduit; a first bleeder conduit connected with said first conduit and with said first bleeder valve, there being a first bleeder timing valve in said first bleeder conduit; a check valve controlled emergency pressure relief conduit connected between said source of pressure fluid and said first conduit; a second feeder conduit connected between said source of pressure fluid and said second conduit and having said second feeder valve therein, said second feeder conduit having a second charger timing valve therein; a second bleeder conduit connected between said second conduit and said second bleeder valve, there being a second bleeder timing valve in said second bleeder conduit; and a mechanical counter operated by force of said piston, whereby gradually augmented pressure fluid force is exerted alternately upon one end of said piston and then upon the other while pressure fluid force is dissipated from the opposite end and a record is made showing the number of each operation.

5. In a flow intermitter of the class described:

right and left end aligned cylinders; a piston member having one of its ends slidable in one of said cylinders and having its other end slidable in the other of said cylinders; a lubricator reservoir upon the end of each of said cylinders; a source of pressure fluid; a first feeder valve, a first bleeder valve, a second feeder valve, and a second bleeder valve, each secured in spaced relation to said piston; means for operating said feeder and bleeder valves by said piston, one feeder valve and one bleeder valve being open while the other feeder valve and the other bleeder valve are closed; first and second receivers for pressure fluid; means for initially charging said receivers with pressure fluid; a first conduit connecting said first receiver and one of said lubricator reservoirs; a second conduit connecting said second receiver and the other said lubricator reservoir; a first feeder conduit adapted for connecting into said source of pressure fluid, with both ends of said first feeder valve, and with said first conduit, there being a first charger timing valve in said first feeder conduit; a first bleeder conduit connected with said first conduit and with said first bleeder valve, there being a first bleeder timing valve in said first bleeder conduit; a second feeder conduit connected between said source of pressure fluid and said second conduit and having said second feeder valve therein, said second feeder conduit having a second charger timing valve therein; a second bleeder conduit connected between said second conduit and said second bleeder valve, there being a second bleeder timing valve in said second bleeder conduit; and a mechanical counter operated by force of said piston, whereby gradually augmented pressure fluid force is exerted alternately upon one end of said piston and then upon the other while pressure fluid force is dissipated from the opposite end, and the operations are numbered in sequence.

6. In a flow intermitter of the class described: right and left end aligned cylinders; a piston member having one of its ends slidable in one of said cylinders and having its other end slidable in the other of said cylinders; a lubricator reservoir upon the end of each of said cylinders; a source of pressure fluid; a first feeder valve, a first bleeder valve, a second feeder valve, and a second bleeder valve, each secured in spaced relation to said piston; means for operating said feeder and bleeder valves by said piston, one feeder valve and one bleeder valve being open while the other feeder valve and the other bleeder valve are closed; first and second receivers; means for initially charging said receivers with pressure fluid; a first conduit connecting said first receiver and one of said cylinders; a second conduit connecting said second receiver and the other said cylinders; a first feeder conduit adapted for connecting into said source of pressure fluid, with both ends of said first feeder valve, and with said first conduit, there being a first charger timing valve in said first feeder conduit; a first bleeder conduit connected with said first conduit and with said first bleeder valve, there being a first bleeder timing valve in said first bleeder conduit; a second feeder conduit connected between said source of pressure fluid and said second conduit and having said second feeder valve therein, said second feeder conduit having a second charger timing valve therein; a second bleeder conduit connected between said second conduit and said second bleeder valve, there being a second bleeder timing valve in said second bleeder conduit; and a mechanical counter operated by force of said piston, whereby gradually augmented pressure fluid force is exerted alternately upon one end of said piston and then upon the other while pressure fluid force is dissipated from the opposite end, and the operations are numbered in sequence.

7. In a flow intermitter of the class described:

force is exerted alternately upon one end of said piston and then upon the other while pressure fluid force is dissipated from the opposite end.

7. In a flow intermitter of the class described: right and left end aligned cylinders; a piston member having one end slidable in one of said cylinders and the other end slidable in the other of said cylinders; means for lubricating said piston and cylinders; a source of pressure fluid; a first feeder valve, a first bleeder valve, a second feeder valve, and a second bleeder valve, each secured in spaced relation to said piston; means for operating said feeder and bleeder valves by said piston, one feeder valve and one bleeder valve being open while the other feeder valve and the other bleeder valve are closed; a first conduit connecting one of said cylinders with said source of pressure fluid; a second conduit connecting the other said cylinder and said source of pressure fluid; a first feeder conduit connected into said source of pressure fluid, with both ends of said first feeder valve and with said first conduit; a first bleeder conduit connected with said first conduit and with said first bleeder valve; a second feeder conduit connected between said source of pressure fluid and said second conduit and having said second feeder valve therein; and a second bleeder conduit connected between said second conduit and said second bleeder valve, whereby said piston is driven alternately in opposite directions to operate said valves as described.

8. In a flow intermitter, the improvement which includes: a piston within a cylinder; an assembly of four valves arranged in pairs and in spaced relation to said piston, one valve of each pair being a feeder valve supplying pressure to one end of said piston, and the other a bleeder valve discharging pressure fluid from the other end; means upon said piston and valves to open one of each said pair while closing the other of each said pair; a first pair of conduits having pressure fluid therein, said conduits being connected to opposite ends of said cylinder; a second pair of conduits connected to one of said first pair of conduits and having pressure fluid therein; and a third pair of conduits connected to the other of said first pair of conduits and having pressure fluid therein, said pairs of conduits and valves being arranged so that pressure fluid will be alternately admitted to and discharged from opposite ends of said cylinder.

9. In a flow intermitter for a well; a cylinder having a piston therein; first and second pairs of feeder and bleeder valves in spaced relation to said piston; first and second conduits, the first connected to one end of said cylinder and the second to the other end; and means upon said piston to alternately open one valve of both said pairs and simultaneously close the other two so as to increase the pressure within one of said conduits and simultaneously decrease the pressure within the other to successively force said piston in opposite directions for purposes described.

10. In a flow intermitter, the improvement which includes: a high pressure supply line; two pairs of valves, each pair comprising a charger and a bleeder valve; a piston and a cylinder in spaced relation to said pairs of valves; means upon said piston to open and close said valves, one of each said pair opening while the others of said pairs close; a first conduit for pressure fluid upon one end of said cylinders; a second conduit for pressure fluid upon the other end of said cylinder; pressure fluid feeder means for said first and second conduits, said feeder means being controlled by one of each said pairs of valves; and bleeder means upon both said conduits, said bleeder means being controlled by the other one of each said pairs of valves, said feeder and bleeder means being adapted to alternately increase and decrease the pressure fluid contacting opposite ends of said piston to successively move same in opposite directions to successively open and close all said valves.
